UNITED STATES PATENT OFFICE.

JEREMIAH E. LANGFORD, JR., OF CEDARHURST, NEW YORK.

RAIL-SUPPORTING MEANS.

Application filed August 8, 1928. Serial No. 298,182.

My invention relates to rail supporting devices, and has relation especially to tie plates, rail chairs or ties for use with or without ties of other constructions.

5 The object of my invention is to provide rail supporting means of the above character which may be used with rails of varying dimensions, particularly with rail bases of varying widths and thicknesses, the construction being such as to tightly hold the rail in place to prevent creeping, spreading, turning or canting. The object is, furthermore, to provide a construction of this kind which may be used with or without other 10 rail supporting devices, such, for example, as ties made of any kind of material, such as wood, concrete, etc. Further objects of my invention will appear from the detailed description thereof contained hereinafter.

15 While my invention is capable of embodiment in many different forms, for the purpose of illustration I have shown only certain forms thereof in the accompanying drawings, in which—

20 Fig. 1 is a plan view of a portion of a tie made in accordance with my invention;

Fig. 2 is a side elevation of the same partly in section;

Fig. 3 is an end elevation of the same;

25 Fig. 4 is an end elevation of a modification of my invention;

Fig. 5 is a plan view of the modification shown in Fig. 4; and

Fig. 6 is a plan view of the assembled construction.

In the form of my invention shown in Figs. 1 to 3 I have shown a rail 1 which is supported upon a tie plate 2. The tie plate 2 has, as shown in Fig. 1, a V-shaped recess 3 having at the sides thereof two inclined wedging surfaces 4 and 5. The wedging surfaces are adapted to support wedging blocks 6 and 7, which have on their inner faces a series of steps 8 and 9 respectively to 30 cooperate with a pyramid-shaped block 10 having similarly stepped faces 11 and 12, the base of which block 10 is arranged to rest against the side of the rail 1. By the adjustment of the blocks 6 and 7 from one 35 stepped position to another with regard to the block 10, the blocks 6, 7 and 10 may be placed so as to fit any width of rail base of the rail 1. For this purpose, if desired, the 40 size of the steps 8, 9, 11 and 12 may be chosen so as to correspond to any series of widths of rail bases. On top of the tie plate 2

there is a dove-tailed recess 13 which is designed to receive a tapered wedging plate 14, one side of which has an angular edge 15 to fit in the recess 13, and the other edge of 45 which has an upwardly tapered face 16 to fit against the rail base, the body of the wedging plate 14 being tapered as shown in Fig. 2. In order to hold the wedging plate 14 securely in place I provide around the tie plate 2 at either side of the rail, a U-shaped clamping member 17, which fits over the top of the tapered wedging plate 14 around the two sides of the tie plate 2, and is provided with inwardly directed projections 18 on the 50 underside of the tie plate 2. If desired, I may provide the clamping plate 17 with bolts 19 having nuts 20 thereon so that the entire device, when in position, may be 55 tightly and permanently secured in place. In assembling the parts the plates 6, 7 and 10 are adjusted into such a stepped relation to each other as to fit against the side of the rail base on one side and against the inclined surfaces 4 and 5 on the other end. The 60 clamping plate 17 is preferably applied over the tie plate 2 and the tapered plate 14 is inserted while the clamping member 17 is pushed over to the left of Fig. 2, adjacent to the rail 1. Thereafter, the clamping member 17 is pushed far to the right towards the thicker end of the wedging plate 14, to tightly clamp the rail base in place, and the bolts 19 are then tightened to secure 65 the parts in final position.

In the form or modification of my invention, as shown in Figs. 4 and 5, the construction and operation are the same as in the previously described form of my invention except in the following respects. In this 70 instance I have provided a tie plate 21 having a transverse recess 22 with only one inclined surface 23 therein. In the recess 22 there is a stepped block 24 adapted to rest at one face against the inclined surface 23, and being provided with a stepped inner face 25 similar to one of the stepped inner faces 8 and 9 in the form of my invention previously described. This is adapted to 75 cooperate with a stepped block 26, the base of which is arranged to rest against the edge of a rail base 27 while the opposite side is provided with an inclined stepped surface 28 to cooperate with the stepped face 25 of the block 24. One end 29 of the block 26 80 is supported by a transverse projection 29' cast on the tie plate 21. There is also pro-

vided a U-shaped clamping member 30, which is constructed the same as the U-shaped clamping member shown in the previous form of my invention. In this instance there is also provided a dove-tailed recess 31 at the top of the tie plate 2 to receive a tapered wedging plate 32 constructed exactly as in the case of the plate 14 in the other form of my invention. The device 10 comprised in the form of my invention as shown in Figs. 4 and 5 is assembled in substantially the same way as in assembling the form of my invention previously described. However, in this instance the stepped block 15 26, as previously referred to, is supported at one side from the rail base and at the opposite side by the stepped surface 25 of the block 24 resting against the inclined surface 23 while one end of the block 26 rests against 20 the projection 29.

As above pointed out, it will be understood that while the devices shown in Figs. 1 to 5 of the drawings are portions of complete ties across the entire track so that each tie 25 supports the two rails in the manner above described, it is to be understood that, instead, each rail may be supplied with separate tie plates or rail chairs, the two ends of the tie plates or rail chairs being constructed 30 on both sides of the particular rail which it holds in place in the manner as shown and described in each one or both of the modified forms of my invention hereinabove described in detail. Also, it is to be understood 35 that the aforesaid devices for holding the rails in place may be used with or without other ties made of wood, metal, cement, or any other material, and in connection with any desired roadbed construction.

40 In Fig. 6 I have shown different ways of supporting the rail holding means. At the top of Fig. 6 I have shown a complete wood tie 2 with the two rails held in place thereon as in the preceding figures, it being understood that the same may or may not be supported on a wooden tie 32'. Also, in the middle of Fig. 6 I have shown a concrete base 33 supporting two tie plates 34 and 35 constructed and equipped as in the forms 50 shown in Figs. 1 to 5, and held in place by bolts 36. At the lower part of Fig. 6 I have shown another way of supporting the rail holding means, the same comprising a steel channel member 37 with two lateral up-standing flanges, said channel member having welded therein two tie holding plates 40 and 41 constructed exactly like the tie holding means shown in Figs. 1 to 5.

Also, it will be understood that in the case 60 where it is desired to secure in place rails of the same width, the stepped blocks 6, 7, 10, 24 and 26 may be omitted, as well as the recesses in which said blocks are placed, so that the tie plate 2 will then fit exactly against the edge of the rail base of

uniform width. Also, it will be understood that, if desired, the bolts 19 may be omitted. Any variations in the thicknesses of the rail bases are taken care of, as will be readily seen, by reason of the fact that the plates 14 and 32 are tapered so that the variations in the thickness of the rail base will be taken care of by appropriate lateral adjustment of the clamping members 17 and 30 when being moved into final position. 75

While I have described my invention above in detail I wish it to be understood that many changes may be made therein without departing from the spirit of the same. 80

I claim:

1. A rail supporting means comprising a rail supporting plate having a recess in which the rail base is adapted to be carried, a wedging plate extending from the rail base 85 to the supporting plate, and a clamping member adapted to cooperate with the wedging plate to hold the rail securely in the supporting plate.

2. A rail supporting means comprising a rail supporting plate having a recess in which the rail base is adapted to be carried, a wedging plate extending from the rail base to the supporting plate, and a U-shaped clamping member adapted to embrace the 95 parts so as to cooperate with the wedging plate to hold the rail securely in the supporting plate.

3. A rail supporting means comprising a rail supporting plate having a recess in 100 which the rail base is adapted to be carried, a wedging plate extending from the rail base to the supporting plate, and a U-shaped clamping member adapted to embrace the parts so as to cooperate with the wedging 105 plate to hold the rail securely in the supporting plate, the free ends of the clamping member having bolts provided therein so as to draw the ends of the same together.

4. A rail supporting means comprising a 110 rail supporting plate having a recess in which the rail base is adapted to be carried, a wedging plate extending from the rail base to the supporting plate in which it is received in a dove-tailed recess therein, and a U-shaped clamping member adapted to embrace the parts so as to cooperate with the wedging plate to hold the rail securely in the supporting plate, the free ends of the clamping member having bolts provided 115 therein so as to draw the ends of the same together.

5. A rail supporting means comprising a rail supporting plate having a recess in 125 which the rail base is adapted to be carried, a wedging plate extending from the rail base to the supporting plate, a clamping member adapted to cooperate with the wedging plate to hold the rail securely in the supporting plate, and a laterally adjust- 130

able holding means for the rail comprising relatively movable wedging blocks extending from the rail base to the supporting plate.

5 6. A rail supporting means comprising a rail supporting plate having a recess in which the rail base is adapted to be carried, a wedging plate extending from the rail base to the supporting plate, a U-shaped 10 clamping member adapted to embrace the parts so as to cooperate with the wedging plate to hold the rail securely in the supporting plate, and a laterally adjustable holding means for the rail comprising relatively 15 movable wedging blocks extending from the rail base to the supporting plate.

7. A rail supporting means comprising a rail supporting plate having a recess in which the rail base is adapted to be carried, 20 a wedging plate extending from the rail base to the supporting plate, a U-shaped clamping member adapted to embrace the parts so as to cooperate with the wedging plate to hold the rail securely in the supporting 25 plate, the free ends of the clamping member having bolts provided therein so as to draw the ends of the same together, and a laterally adjustable holding means for the rail comprising relatively movable wedging blocks 30 extending from the rail base to the supporting plate.

8. A rail supporting means comprising a rail supporting plate having a recess in which the rail base is adapted to be carried, 35 a wedging plate extending from the rail base to the supporting plate in which it is received in a dove-tailed recess therein, a U-shaped clamping member adapted to embrace the parts so as to cooperate with the 40 wedging plate to hold the rail securely in the supporting plate, the free ends of the clamping member having bolts provided therein so as to draw the ends of the same together, and a laterally adjustable holding 45 means for the rail comprising relatively movable wedging blocks extending from the rail base to the supporting plate.

9. A rail supporting means comprising a rail supporting plate having a recess in 50 which the rail base is adapted to be carried, a wedging plate extending from the rail base to the supporting plate, a clamping member adapted to cooperate with the wedging plate to hold the rail securely in the supporting 55 plate, and a laterally adjustable holding means for the rail comprising relatively movable wedging blocks having stepped interacting faces extending from the rail base to the supporting plate.

60 10. A rail supporting means comprising a rail supporting plate having a recess in which the rail base is adapted to be carried, a wedging plate extending from the rail base to the supporting plate, a U-shaped 65 clamping member adapted to embrace the

parts so as to cooperate with the wedging plate to hold the rail securely in the supporting plate, and a laterally adjustable holding means for the rail comprising relatively 70 movable wedging blocks having stepped interacting faces extending from the rail base to the supporting plate.

11. A rail supporting means comprising a rail supporting plate having a recess in which the rail base is adapted to be carried, a wedging plate extending from the rail base to the supporting plate, a U-shaped 75 clamping member adapted to embrace the parts so as to cooperate with the wedging plate to hold the rail securely in the supporting plate, the free ends of the clamping member having bolts provided therein so as to draw the ends of the same together, and a laterally adjustable holding means for the rail comprising relatively 80 movable wedging blocks having stepped interacting faces extending from the rail base to the supporting plate.

12. A rail supporting means comprising a rail supporting plate having a recess in 90 which the rail base is adapted to be carried, a wedging plate extending from the rail base to the supporting plate in which it is received in a dove-tailed recess therein, a U-shaped 95 clamping member adapted to embrace the parts so as to cooperate with the wedging plate to hold the rail securely in the supporting plate, the free ends of the clamping member having bolts provided therein so as to draw the ends of the same together, and a laterally adjustable holding means for the rail comprising relatively 100 movable wedging blocks having stepped interacting faces extending from the rail base to the supporting plate.

13. A rail supporting means comprising a rail supporting plate having a recess in which the rail base is adapted to be carried, and a holding means for the rail base comprising laterally adjustable blocks having stepped interacting faces for supporting the rail laterally in the supporting plate.

14. A rail supporting means comprising a rail supporting plate having a recess in which the rail base is adapted to be carried, and a holding means for the rail base comprising a clamping member and laterally adjustable blocks having stepped interacting faces for supporting the rail laterally in the supporting plate, one of said blocks being adapted to be supported from an inclined face in the rail supporting plate and the inside of the clamping member, and the other block being adapted to be supported from the side of the rail base.

15. A rail supporting means comprising a rail supporting plate having a recess in which the rail base is adapted to be carried, and a holding means for the rail base comprising a U-shaped clamping member 130

adapted to embrace the rail supporting plate and laterally adjustable blocks having stepped interacting faces for supporting the rail laterally in the supporting plate, one of said blocks being adapted to be supported from an inclined face in the rail supporting plate and the inside of the clamping member and the other block being adapted to be supported from the side of the rail base.

10 16. A rail supporting means comprising a rail supporting plate having a recess in which the rail base is adapted to be carried, and a holding means for the rail base comprising a U-shaped clamping member adapted to embrace the rail supporting plate

and laterally adjustable blocks having stepped interacting faces for supporting the rail laterally in the supporting plate, one of said blocks being adapted to be supported from an inclined face in the rail supporting plate and the inside of the clamping member and the other block being adapted to be supported from the side of the rail base and the ends of the clamping member being adapted to be held together with bolts. 20

In testimony that I claim the foregoing, I have hereunto set my hand this 27th day of July, 1928. 25

JEREMIAH E. LANGFORD, JR.
